Primary Examiner — Garth Rademaker*Assistant Examiner* — Melanie Pellegrini*(74) Attorney, Agent, or Firm* — Jackson Walker L.L.P.(57) **CLAIM**

The ornamental design for a pant pocket, as shown and described.

DESCRIPTION

FIG. 1 is a front perspective view of a pant pocket showing our new design;

FIG. 2 is a front elevation view thereof;

FIG. 3 is a rear elevation view thereof;

FIG. 4 is a right-side elevation view thereof;

FIG. 5 is a front perspective section views taken along lines 5-5 shown in FIG. 1; and,

FIG. 6 a front elevation section view taken along lines 6-6 shown in FIG. 4.

The broken lines shown in the drawings illustrate environmental matter and form no part of the claimed design.
